UNITED STATES PATENT OFFICE.

FRANK HEDLEY, OF YONKERS, AND JAMES S. DOYLE, OF NEW YORK, N. Y.

TIME-RECORDING DEVICE FOR ELECTRIC TRAINS.

1,020,420.

Specification of Letters Patent. Patented Mar. 19, 1912.

Application filed May 17, 1910. Serial No. 561,799.

To all whom it may concern:

Be it known that we, FRANK HEDLEY and JAMES S. DOYLE, both citizens of the United States, residing at Yonkers, county of Westchester, and State of New York, and New York, county and State of New York, respectively, have invented certain new and useful Improvements in Time-Recording Devices for Electric Trains and the Like, of which the following is a full, clear, and exact description.

In the operation of electric railways it has been found that considerable power is wasted by unskillful or careless motormen, who fail to take full advantage of opportunities for "coasting," that is, allowing the train to run under its own momentum, without taking current from the line, as for example down a slight grade, or on a level stretch of track, or in approaching a station. Various means have therefore been devised for keeping some sort of a check on the motormen, so that knowledge of their work may be gained, with the object of ascertaining who of them are exercising skill and care in handling their trains. In such case suitable rewards or bonuses can be offered to the motormen, based upon the power or current saved as determined by the information afforded by the registering devices. In a prior patent granted to us November 23, 1909, No. 940,810, we have described and claimed broadly means for recording the time or portion of a "run" spent in coasting, that is, running with current and brakes both "off." In general it is found that for determining the motorman's saving or waste of power this coasting time is the most advantageous basis; but there are circumstances in which it is desirable to know other items as well, as for example to serve as a check on other records. For this purpose we have been led to devise our present invention, which has for its chief object to provide apparatus for recording not only the "coasting" time, but also the time during which current is "on," the time during which the brakes are on, and the total time of the run or trip.

A further object is to provide apparatus for this purpose, which shall be of the simplest possible character and withal thoroughly reliable in operation.

To these and other ends the invention consists in the novel features of construction

and combinations of elements hereinafter described.

A convenient and effective embodiment of the invention is illustrated in the accompanying drawing, in which—

Figure 1 is a diagram of the apparatus, showing the wiring thereof. Fig. 2 is a diagrammatic plan view of the recording device. Fig. 3 is a diagrammatic sectional view of a portion of the recording device, on line 3—3 of Fig. 2. Fig. 4 is a sectional plan view of an electric car with our recording device installed therein.

The time-recording device has four time-printing wheels, 4, 5, 6, 7, the first of which is employed for recording the total time of the run or trip, the second for recording the total time during which the driving motor or motors were taking current from the line, the third for recording the total time during which the brakes were on, and the fourth for recording the total time during which the vehicle was "coasting." Suitably connected to the respective time-printing wheels 4, 5, 6, 7, are four driving gears 8, 9, 10, 11, which are rotated through the instrumentality of four connecting gears 12, 13, 14, 15, in mesh with gears 16, 17, 18, 19, fast on a shaft 20 which is continuously driven by a clock, indicated at 21. The connecting gear 12, transmitting motion from the clock-driven gear 16 to the driving gear 8, is mounted in fixed bearings, so that the three gears just mentioned are always in mesh. Consequently the time-printing wheel 4 revolves continuously while the clock is running. The other connecting gears, however, are mounted in forks 22, 23, 24, capable of being raised and lowered to throw the said gears out of and into mesh with the respective driving and clock-driven gears. The forks are normally held in elevated position by springs 25 but may be drawn down against the tension of the springs by electromagnets 5^a, 6^a, 7^a. It will therefore be seen that the driving gears 9, 10, 11, and hence the associated time-printing wheels 5, 6, 7, are capable of intermittent operation; each time-printing wheel turning as long as its connecting gear is held in depressed position by the associated electromagnet, and remaining at rest as long as the electromagnet is deenergized and the connecting gear held in raised position by its spring 25.

According to our invention the time-printing wheels 5, 6, 7, are under the control of the motor- and brake-controlling instrumentalities of the train in such manner that as long as current is on the driving motor or motors the time-printing wheel 5 will be in operation, while the time-printing wheel 6 will operate only during the time the brakes are on, and the time-printing wheel 7 only during the time the current and brakes are both off. The preferred means for this control will now be described.

The switch 26 is intended to indicate any suitable electric controller for controlling the driving motor or motors, and the conductor 27 indicates the motor-circuit, capable of being closed and broken by the controller 26. The valve 28 indicates the brake-controller, by which the brakes are applied and released.

The solenoid 29, having a plunger or armature 30, is connected with a suitable source of current and is associated with the controller 26 in such way as to be energized whenever the controller is manipulated to deliver driving current to the motor or motors. For this purpose the solenoid may have one terminal connected to the conductor 27, through a suitable resistance 31, and the other terminal grounded, as at 32. It will therefore be seen that when the circuit represented by the conductor 27 is closed, that is, when current is being supplied to the driving motors, the solenoid will be energized and will raise its armature 30. This armature carries two bridge pieces 33, 34, the former of which, when the solenoid is deenergized, rests on a pair of contacts 35, 36, the first connected by a wire 37 through a resistance 38 to a suitable source of current indicated by the battery 39, the other terminal of said source being connected to ground at 40, the second, 36, connected by a wire 41 to first of two contacts 42, 43. Above the bridge piece 33 are two contacts 44, 45, the first connected by wire 46 through a resistance 47 to the source 39, in parallel with the wire 37, while the second, 45, is connected by wire 48 to one of a pair of contacts 49, 50, and by a wire 51, joined to wire 48, to one terminal of an auxiliary solenoid 52, the other terminal of which is grounded at 53. The last named solenoid has a plunger or armature 54 carrying two bridge pieces 55, 56, and resting on a stop 52^a when the solenoid is deenergized, with the bridge pieces disengaged from contacts 42-43 and 49-50. Contact 43 is connected by wire 57 to the first of a pair of contacts 58, 59, the latter of which is connected by a wire 60 with one terminal of magnet 7^a, the other terminal of the magnet being connected to ground at 61 through wire 62. Contact 50 is connected by a wire 63 to the first of a pair of contacts 64, 65, of which the latter,

65, is connected by wires 66 and 67 to wire 46. Coöperating with contacts 58-59, 64-65, are two bridge pieces 68, 69, sliding on a rod or guide 70 and connected together by a coil spring 71. The bridge piece 69 is also connected by a coil spring 72 to a block 73, also sliding on the guide 70, and the block just mentioned is connected by a bar 74 to the piston 75 of the brake cylinder 76. When the brakes are "off" the piston stands in the position shown, with the bridge pieces 68, 69, in engagement with their respective pairs of contacts; but when the controller 26 is manipulated to apply the brakes, compressed air is admitted to the rear of the brake cylinder through a pipe 77 from a pipe 78 leading from a compressed air reservoir, not shown. The piston is thereby advanced, carrying the bridge pieces away from their contacts and bringing bridge piece 68 into engagement with a pair of contacts 79, 80, the first of which is connected by a wire 81 to wire 67, and the second by wire 82 to one terminal of magnet 6^a. The other terminal of this magnet is connected to wire 62 and thence to ground. Above the bridge piece 34, carried by the armature of solenoid 29, are two contacts 83, 84, the first connected to wire 37 by a wire 85 and the second by a wire 86 to one terminal of magnet 5^a. The other terminal of this magnet is connected to wire 62 and thence to the ground 61.

The operation of the system will now be readily understood. The parts being in the positions shown in Fig. 1, a card or slip of paper is inserted between the platen 87 and the ink ribbon 88, in front of the time-printing wheels. The platen is then actuated, by any suitable means, not shown, thus making an imprint on the card or slip of paper. The imprint may, for example, read 00 00 00 M 12 00. The motorman now closes the motor-circuit to start the car or train, whereupon current flows through resistance 31 and solenoid 29 to ground 32. The solenoid, thus energized, raises its armature, bringing the bridge pieces 33 and 34 into engagement with contacts 44-45, and 84-85, respectively, and thereby establishing a circuit from ground 40 and battery 39 through wires 37 and 85, contact 83, bridge piece 34, contact 85, wire 86, magnet 5^a and wire 62 to ground 61. The magnet 5^a thereupon draws down the connecting gear 12, which starts the time-printing wheel 5 as previously described. At the same time current flows from wire 48 through wire 51 and solenoid 52 to ground 53, thereby energizing solenoid 52, which raises its armature off of stop 52^a and brings the bridge pieces 55 and 56 into engagement with contacts 49-50 and 42-43 respectively. A parallel or shunt sustaining circuit is thus established around con-

acts 44-45, from ground 40 and battery 39 through resistance 47, wires 46, 67, and 66, contact 65, bridge piece 69, contact 64, wire 63, contact 50, bridge piece 55, contact 49, wires 48 and 51, and solenoid 52 to ground 53, thereby keeping this solenoid energized and its armature raised even when the solenoid 29 is deenergized by movement of the controller 26 to off position.

10 Suppose, now, that the motorman desires to coast. Opening the controller switch to throw off the current deenergizes solenoid 29, as just stated, whereupon its armature drops, breaking the circuit through contacts 83, 84, and bridge piece 34. The magnet 5^a is thus deenergized and allows the connecting gear to be lifted by its spring 25, stopping the time-printing wheel 5. At the same time the reengagement of bridge piece 20 33 with contacts 35-36 closes a circuit from ground 40 and battery 39 through resistance 38, wire 37, contact 35, bridge piece 33, contact 36, wire 41, contact 42, bridge piece 56, contact 43, wire 57, contact 58, bridge piece 25 68, contact 69, wire 60, magnet 7^a and wire 62 to ground 61. The magnet 7^a, thus energized, draws down the connecting gear 15 and starts the time-printing wheel 7, which it will be remembered, takes account of the 30 time spent in coasting. Having coasted for a time, it may be necessary for the motorman to throw on the current again, in which case the circuit last traced is broken by the reenergization of solenoid 29; whereupon 35 the coasting-record time-printing wheel 7 is arrested, and the current wheel 5 is again set in operation, as previously described. Or, suppose that while coasting the brakes are applied. The piston 75 carries the 40 bridge pieces 68, 69 away from contacts 58-59 and 64-65, breaking the circuit of the magnet 7^a previously traced through contacts 58-59 and also breaking the shunt circuit, through contacts 42-43 and 64-65, 45 which kept the solenoid 52 energized. The coasting-record wheel 7 is thus arrested and the armature of solenoid 52 is allowed to drop. At the same time, the movement of the piston 75 brings the bridge piece 68 into 50 engagement with contacts 79, 80, and establishes a circuit from ground 40 and battery 39 through resistance 47, wires 46, 67, and 81, contact 79, bridge piece 68, contact 80, wire 82, and magnet 6^a to wire 62 and ground 61. The magnet 6^a then draws down the connecting gear 14 and starts the time-printing wheel 6, which takes account of the time during which the brakes are on. Upon release of the brakes by manipulation of the controller 28 the air escaping through pipe 7 allows the piston to be retracted in the usual way, and leaving all the controlling circuits open as in Fig. 1. Suppose, now, that with the current on (and hence with 55 solenoids 29 and 52 both energized and the

current-on wheel 5 in operation) the brakes should be applied. The current-on circuit, through contacts 83-84 and bridge piece 34, will not be disturbed, but the brakes-on circuit through contacts 79-80 and bridge piece 68 will be established in addition. The car or train having completed the run the card or slip is inserted in the recorder again and a second imprint taken, reading, for instance, 33 19 72 P2 04, thus showing that in a run of two hours and four minutes the train coasted thirty-three minutes in all, that the brakes were on for nineteen minutes, and that the driving motor or motors "took current from the line for a time amounting in all to seventy-two minutes. This record card, made by the motorman himself, thus constitutes a permanent record upon which to determine what part, if any, he is to receive of any reward or bonus offered for efficient work.

The printing devices, the clock, the various electromagnets and solenoids, the battery 39, etc., may be located in any convenient part of the car, as for example in a suitable casing 90 in the vestibule, as in Fig. 4.

It is to be understood that the invention is not limited to the specific construction and arrangement herein illustrated and described, but is capable of other embodiments without departure from its proper spirit and scope.

We claim:

1. The combination with the motor- and brake-controllers of an electrically propelled vehicle; of a plurality of independently operable time-printing devices; means under the control of the motor-controller for setting one of said time-printing devices in operation whenever current is delivered to the driving motor of the vehicle; means under the control of the brake-controller for setting another of said time-printing devices in operation whenever the brakes are applied; and means operating when the current is thrown off while the brakes are off, to set another of said time-printing devices in operation; whereby separate records may be made of the total time of current on, the total time of brakes on, and the total time of brakes and current off.

2. The combination with the motor- and brake-controllers of an electrically propelled vehicle; of a plurality of independently operable time-printing devices; an electromagnetic mechanism for each of said devices to start and arrest the same; independent energizing circuits for the electromagnetic mechanisms; electromagnetic means, dependent for operation upon manipulation of the motor-controller to deliver current to the driving motor of the vehicle, for controlling one of said circuits whereby one of said time-printing devices

may record the time of current on; means, dependent for operation upon manipulation of the brake-controller to apply the brakes, for controlling another of said circuits independently of the said electromagnetic circuit-controlling means, whereby another of said time-printing devices may record the time of brakes on; and means controlling another of said circuits to cause actuation of the associated electromagnetic mechanism when the current is thrown off while the brakes are off, whereby said associated electromagnetic mechanism will set in operation another of the time-printing devices to record the time of current and brakes off.

3. The combination with the motor- and brake-controllers of an electrically propelled vehicle; of a plurality of time-printing devices; an electromagnetic mechanism for each of said devices to start and arrest the same; a coasting circuit for one of said mechanisms to maintain its associated time-printing device in operation as long as said circuit is closed; a circuit for another of the electromagnetic mechanisms under the control of the motor-controller, whereby manipulation of the motor-controller to deliver current to the driving motor of the vehicle will close the last named circuit and start its associated time-printing device; means, actuated by the closing of the last named circuit, to open the coasting circuit; a brake-controlled circuit for another of the electromagnetic mechanisms, under the control of the brake-controller, whereby manipulation of the brake-controller to apply the brakes will close the last named circuit and start its associated time-printing device; means, actuated by the closing of said brake-controlled circuit, for opening the said coasting circuit and means for closing the coasting circuit to start the associated time-printing device when the current is thrown off the motor while the brakes are off.

4. The combination with the motor- and brake-controllers of an electrically propelled vehicle; of a time-printing device for recording the time during which the current and brakes are both off; a controlling circuit permitting the said time-printing device to operate; a second time-printing device for recording time during which current is on the driving motor of the vehicle,

and a controlling circuit normally preventing the operation of the second time-printing device; a third time-printing device for recording the time during which the brakes are on, and a controlling circuit normally preventing the operation of the third time-printing device; means, dependent for operation upon manipulation of the motor-controller, for making and breaking the second controlling circuit; means, dependent for operation upon manipulation of the brake-controller, for making and breaking the third controlling circuit; and making and breaking means in the first controlling circuit, operating through the instrumentality of said first controlling circuit to arrest the first time-printing means whenever the motor-controller is manipulated to deliver current to the driving motor of the vehicle or the brake controller is manipulated to apply the brakes.

5. The combination with the motor- and brake-controllers of an electrically propelled vehicle; of a continuously clock-driven time-printing device for recording the total time of a trip; clock-driven time-printing devices capable of intermittent operation, for recording separately the total time of current-on, the total time of brakes-on, and the total time of current and brakes off; means, under the control of the motor-controller, for setting the current-on time-printing device in operation whenever the motor-controller is manipulated to deliver current to the driving motor of the vehicle; means, under the control of the brake-controller, for setting the brakes-on time-printing device in operation whenever the brake-controller is manipulated to apply the brakes; and means for setting in operation the remaining time-printing device when the motor controller is manipulated to cut off the current from the driving motor while the brakes are off.

In testimony whereof we affix our signatures in the presence of two subscribing witnesses.
